[57] **CLAIM**

The ornamental design for a fishing lure storage device, as shown and described.

DESCRIPTION

FIG. 1 is a perspective view of the design for fishing lure storage device, which is the subject of this invention;

FIG. 2 is a plan view thereof;

FIG. 3 is a bottom view thereof;

FIG. 4 is a side view thereof; and

FIG. 5 is a rear view thereof.

The side opposite to that shown in FIG. 4 is a mirror image of FIG. 4.
